Attest:

UNITED STATES PATENT OFFICE.

GARDINER C. SIMS, OF PROVIDENCE, RHODE ISLAND, ASSIGNOR TO THE
ARMINGTON & SIMS ENGINE COMPANY, OF SAME PLACE.

LUBRICATOR.

SPECIFICATION forming part of Letters Patent No. 292,446, dated January 22, 1884.

Application filed August 25, 1883. (No model.)

To all whom it may concern:

Be it known that I, GARDINER C. SIMS, of the city and county of Providence, and State of Rhode Island, have invented a new and useful Improvement in Lubricators; and I hereby declare the following to be a full, clear, and exact description of the same, reference being had to the accompanying drawings, forming part of this specification.

10 This invention has reference to an improvement in lubricators for the eccentrics for steam-engines; and it consists in the peculiar and novel arrangement, in connection with an eccentric, of a funnel of the length of the throw 15 of the eccentric, and an oil-chamber constructed to deliver the oil into the funnel, as will be more fully set forth hereinafter.

In steam-engines, and particularly in the modern high-speed engines, all parts must be 20 thoroughly lubricated to prevent friction and heating. In most parts the ordinary oil-cup can be used; but on the eccentric the ordinary cup cannot be used successfully, owing to the motion of the eccentric.

25 Figure 1 is a side view of an eccentric provided with my improved lubricator, shown partly in section. Fig. 2 is an end view of the same, showing the bracket for supporting the oil-cup.

30 In the drawings, *a* is the crank-shaft. *b* is the eccentric. *c* is the eccentric strap or ring. *d* is the connecting-rod; *e*, a funnel secured to the eccentric-ring *c*, and connecting by a hole with the bearing-surface. The funnel *e* is of a width less than the width of the eccentric, so as not to project over the sides of the same, as in the modern high-speed engine all parts 35 are built so close together that any device wider than the eccentric could not be used.

40 The length of the funnel *e* is equal to or more than the throw of the eccentric.

f is a bracket by which the oil-cup *g* is supported over the funnel *e*, and at all parts of the motion of the funnel will deliver the oil into the same. The oil-cup *g* is provided with 45 any one of the well-known devices for regulating the supply of oil, and as the oil-cup is a fixture, the same may be at all times regulated and supplied with oil. With this device the eccentric of the highest-speed engine 50 can be well and thoroughly lubricated without waste of oil, as only drops fall into the funnel, and no oil in mass is ever contained therein to be affected by the motion of the eccentric.

Having thus described my invention, I claim 55 as new and desire to secure by Letters Patent—

1. An improved lubricator for steam-engines, consisting of a fixed reservoir for the bulk of lubricant, and an attachment secured to a moving part of the machine, for conveying the lubricant from the reservoir to the bearing-surfaces of said moving part, the said attachment being at its receiving end of greater length than the throw of said moving part, whereby the lubricant is at all times received 65 from the reservoir.

2. The combination, with an engine-eccentric, of a funnel secured to the eccentric, and a reservoir fixed upon a rigid portion of the engine, the mouth of said funnel being of 70 greater length than the throw of the eccentric, for the purposes set forth.

3. In a steam-engine, the combination, with the eccentric *b* and ring *c*, of the funnel *e*, the oil-cup *g*, and the bracket *f*, constructed to 75 lubricate the eccentric from a fixed reservoir, as described.

GARDINER C. SIMS.
